TO GUS V. R. MECHIN, OF ST. LOUIS, MISSOURI.

ANTISEPTIC ATTACHMENT FOR TELEPHONES.

No. 900,447.

Specification of Letters Patent.

Patented Oct. 6, 1908.

Application filed January 24, 1908. Serial No. 412,515.

To all whom it may concern:

Be it known that I, FRANK C. TABLER, a citizen of the United States, residing at St. Louis, Missouri, have invented a certain new and useful Improvement in Antiseptic Attachments for Telephones, of which the following is a full, clear, and exact description, such as will enable others skilled in the art to which it appertains to make and use the same, reference being had to the accompanying drawings, forming part of this specification, in which—

Figure 1 is a side elevational view, partly in vertical section, of my improved antiseptic attachment for telephones; Fig. 2 is a front elevation of said device; Fig. 3 is an enlarged detail sectional view showing the means for securing the cap or cover to the receptacle that contains the antiseptic material; Fig. 4 is a side elevation, partly in section, illustrating another way in which the piece of fabric can be arranged in position; Fig. 5 is a sectional view taken on the line 5—5 of Fig. 4; Fig. 6 is a vertical sectional view of a modified form of my invention; Fig. 7 is an enlarged detail view of the device shown in Fig. 6 for the purpose of more clearly illustrating the means that retains the piece of fabric in position; and Fig. 8 is a side elevation, partly in section, of still another form of my invention.

This invention relates to antiseptic attachments for telephones.

The main object of my invention is to provide a device of the character described comprising a piece of fabric arranged in front of the diaphragm of a telephone transmitter and in alignment therewith, and means for supplying said piece of fabric with an antiseptic material.

Other objects of my invention will be hereinafter pointed out.

Preferably, the antiseptic material or solution is supplied to the piece of fabric above referred to by capillary attraction, and said material is contained in a reservoir or receptacle located adjacent to said piece of fabric.

Referring to Fig. 1 of the drawings which illustrates the preferred form of my invention, 1 designates the face plate of an ordinary transmitter, said face plate carrying the diaphragm 2 behind which a carbon button 3 is arranged. An inclosing casing or housing 4 of usual construction is secured to the face plate 1 and on the front side of said face plate

is a threaded boss 1^a which is adapted to receive the hard rubber mouth-piece that transmitters are usually provided with.

The parts above described are herein shown as being mounted on a standard A, but it will, of course, be understood that they could be arranged in a box or any other suitable support.

My improved antiseptic attachment comprises a reservoir or receptacle 5 connected to the face plate 1 and provided with a removable cap or cover 6, the connection between the receptacle 5 and face plate 1 preferably being effected by means of a screw-threaded flange 7 on the receptacle 5 which screws into the boss 1^a on the face plate. A piece of fabric 8 is arranged in front of the diaphragm 2 of the transmitter and in alignment therewith and said piece of fabric is supplied with an antiseptic solution by means of packing or absorbent material 9 arranged inside of the receptacle 5 and saturated with some suitable antiseptic solution.

The receptacle or casing 5 is provided with a central opening that is surrounded by a flange 10 and the piece of fabric 8 is stretched over said flange and across said opening so that it lies parallel to the diaphragm 2, the marginal edges of said fabric being in contact with the packing 9 so that the antiseptic solution with which the packing 9 is saturated will be supplied to the piece of fabric 8 by capillary attraction and thus keep said piece of fabric moist.

In the form of my invention shown in Fig. 1, the cap or cover 6 for the receptacle 5 is provided with an integral mouth-piece B and openings are formed in said cap to receive wicks 11 or short pieces of fibrous material that contact at their inner ends with a fibrous pad 12 which is interposed between the packing 9 and the cap 6 so as to antisepticize the mouth-piece B. Said pad 12 is, of course, provided with a central opening so as not to cover that portion of the piece of fabric 8 which extends across the opening leading to the diaphragm.

If desired, a screen 13 can be arranged over the piece of fabric 8 to prevent it from being broken, and said screen is preferably provided with teeth or projections that are bent down into engagement with the packing 9, as shown in Fig. 1. The removable cap or cover 6 can be connected to the receptacle 5 by any suitable means but I prefer to

- retain said cap in position by means of screws 14 in the edge portion of the receptacle which extend into a groove or channel in a flange 15 on the cap, as shown in Fig. 3. 5 The advantage of connecting the cap to the receptacle in this manner is that the cap can be so adjusted that the printing thereon, such for example, as the trade name of the device, will be arranged properly.
- 10 An antiseptic attachment of the construction above described can be applied easily to telephones of the types in general use by simply removing the mouth-piece from the face plate 1 of the transmitter and screwing 15 the receptacle 5 onto same.
- The piece of fabric 8 that is arranged in alignment with the diaphragm 2 and in front of same, does not interrupt the sound waves, and as said piece of fabric is imperforate, it 20 is impossible for germs to enter the chamber or casing containing the diaphragm. Furthermore, both the mouth-piece and diaphragm are thoroughly antisepticized. The reservoir or receptacle which contains the 25 packing or absorbent material 9 saturated with the antiseptic solution, will keep the piece of fabric 8 moist for a long time, and to renew or replenish the antiseptic medium it is only necessary to saturate the packing 9.
- 30 While I prefer to arrange the piece of fabric 8 between the mouth-piece and the diaphragm, as shown in Fig. 1, I do not wish it to be understood that my broad idea is limited to such a construction as the same results would be accomplished if the piece of fabric were arranged inside of the mouth-piece. In Figs. 4 and 5 I have illustrated such a construction, the piece of fabric 8^a being stretched across the mouth-piece B' 40 adjacent the inner end thereof and retained in position by means of a spring ring 16 which forces the marginal edges of the fabric into a groove on the inner face of the mouth-piece, as shown clearly in Fig. 4. The piece 45 of fabric 8^a contacts with the wicks 11 which lead from the pad 12 that bears upon the packing 9 so that the antiseptic solution is supplied to the fabric 8^a by capillary attraction and thus keeps said fabric moist.
- 50 In Fig. 6 I have shown a slightly modified form of my invention wherein the cap or cover 6^a for the receptacle 5^a is provided with a threaded boss 10^a to receive the hard rubber mouth-piece B^a that was removed from the face plate of the transmitter when the antiseptic attachment was applied to said face plate. The cap piece or cover 6^a in this form of my attachment is provided with a screw-threaded flange 15^a that screws into an 55 internally screw-threaded flange 14^a on the receptacle 5^a and the piece of fabric 8 is held stretched across the opening that leads to the diaphragm of the transmitter by means of a spring clip 17 having radial enlargements that bear upon the packing or absorb- 60 ent material 9 and hold it in position. If the mouth-piece B^a is provided with a perforated partition 18 such as the mouth-pieces in general use are provided with, it will not be necessary to arrange a screen over the 70 piece of fabric 8 to prevent it from being broken, but in case said mouth-piece is not so constructed, it is preferable to arrange a screen 19 over the fabric, as shown in Fig. 7. The central opening in the receptacle is surrounded by a threaded hollow boss 7^a that co-operates with the boss 1^a on the face plate to retain the receptacle in position, and if desired, said receptacle may be provided with a spring clip 20 having a bent end that 80 extends behind the face plate 1, the other end of said clip being secured to the upper edge of the hollow boss 7^a and lying underneath the piece of fabric 8 that is stretched across said boss. With a construction of this 85 description, the receptacle 5^a cannot be unscrewed from the face plate without first removing the cap piece 6^a and the piece of fabric 8 so as to get at the clip 20.
- In Fig. 8 I have shown still another form 90 of my invention wherein the face plate 1 of the transmitter has a receptacle or reservoir 5^b formed integral therewith to receive the packing or absorbent material, the other features of this form being the same as the form 95 shown in Fig. 6. Any suitable antiseptic material can be used such, for example, as formaldehyde, carbolic acid, wintergreen or oil of cassia, but it will, of course, be understood that it is immaterial so far as my invention 100 is concerned what kind of antiseptic material is used.
- Having thus described my invention, what I claim as new and desire to secure by Letters Patent is:
1. An antiseptic attachment for telephones, comprising fibrous material arranged in front of, and parallel to, the diaphragm of a telephone, and means for supplying said fibrous material with an antiseptic medium; 110 substantially as described.
2. An antiseptic attachment for telephones, comprising fibrous material arranged in front of the diaphragm of a telephone and in alignment therewith, and absorbent material saturated with an antiseptic compound for keeping said fibrous material moist; substantially as described.
3. An antiseptic attachment for telephones, comprising an imperforate piece of fabric arranged in front of the diaphragm of a telephone in such a manner that it is penetrated by the sound waves of the voice of the person using the telephone, and means for supplying said fabric with an antiseptic medium; substantially as described.
4. An antiseptic attachment for telephones, comprising an imperforate piece of fabric arranged in front of the diaphragm of a telephone in such a manner that it is pene- 130

- trated by the sound waves of the voice of the person using the telephone, and absorbent material saturated with an antiseptic solution which is supplied to said piece of fabric by capillary attraction; substantially as described.
5. An antiseptic attachment for telephones, comprising a piece of fabric arranged in front of the diaphragm of a telephone and 10 extending parallel to said diaphragm, and a receptacle or reservoir containing an antiseptic medium which keeps said piece of fabric moist; substantially as described.
6. An antiseptic attachment for telephones, comprising a receptacle arranged on the face plate of a telephone transmitter and provided with a central opening that is in alinement with the diaphragm, and a piece of fabric arranged in alinement with said opening and extending transversely thereof, said piece of fabric being kept moist by the antiseptic medium in said receptacle; substantially as described.
7. An antiseptic attachment for telephones, comprising a reservoir or receptacle provided with a central opening that is in alinement with the diaphragm, a mouth-piece on said receptacle, a piece of fabric which extends transversely of the central 25 opening in said receptacle, and an antiseptic medium in said receptacle for keeping said piece of fabric moist; substantially as described.
8. An antiseptic attachment for telephones, comprising a piece of fabric arranged across the opening to the diaphragm of the telephone, in combination with a reservoir containing antiseptic material which supplies said fabric; substantially as described.
- 40 9. An antiseptic attachment for telephones, comprising a receptacle having a central opening that is located in alinement with the diaphragm of a telephone, a detachable cap for said receptacle, a mouth-piece carried by said cap, a piece of fabric arranged transversely of the central opening in said receptacle, and an antiseptic medium in said receptacle which supplies said piece of fabric; substantially as described.
- 50 10. An antiseptic attachment for telephones, comprising a receptacle provided with a central opening located in alinement with the diaphragm of a telephone and containing an antiseptic medium, a piece of fabric extending transversely of said opening and adapted to be kept moist by the antiseptic medium, and a cap or cover for said receptacle provided with an integral mouth-piece; substantially as described.
- 55 11. An antiseptic attachment for telephones, comprising a receptacle or reservoir containing an antiseptic medium, a piece of fabric arranged in alinement with the diaphragm of the telephone on which said attachment is used, the antiseptic medium in
- said receptacle being supplied to said piece of fabric by capillary attraction, a mouth-piece, and means for conducting the antiseptic medium to the interior of said mouth-piece; substantially as described.
12. An antiseptic attachment for telephones, comprising a receptacle adapted to be connected to the face plate of a telephone transmitter and provided with a central opening that is in alinement with the diaphragm, a piece of fabric arranged across said opening, absorbent material in said receptacle saturated with an antiseptic solution for keeping said piece of fabric moist, a cover detachably connected to said receptacle and provided with an integral mouth-piece, and means for conducting said antiseptic solution to the interior of said mouth-piece; substantially as described.
13. An antiseptic attachment for telephones, comprising a receptacle provided with a central opening, a mouth-piece carried by said receptacle, a piece of fabric arranged inside of said mouth-piece and extending transversely thereof, and an antiseptic medium in said receptacle for keeping said fabric moist; substantially as described.
14. An antiseptic attachment for telephones, comprising a receptacle which contains an antiseptic medium, said receptacle having a central opening that is in alinement with the diaphragm of a telephone, a mouth-piece carried by said receptacle, a piece of fabric arranged inside of said mouth-piece and extending transversely thereof, yielding means for retaining said piece of fabric in position, and means for supplying the antiseptic medium in said receptacle to said piece of fabric; substantially as described.
15. An antiseptic attachment for telephones, comprising a receptacle provided with a central opening and containing an antiseptic medium, an adjustable cover on said receptacle which carries a mouth-piece, and a piece of fabric extending transversely of the opening in said receptacle and being kept in a moist condition by the antiseptic medium; substantially as described.
16. An antiseptic attachment for telephones, comprising a receptacle provided with a central opening that is surrounded by a flange, a piece of fabric stretched across said opening, absorbent material in said receptacle saturated with an antiseptic solution to keep said fabric moist, a screen arranged over said fabric, and a mouth-piece carried by a cap that is connected to said receptacle; substantially as described.
17. An antiseptic attachment for telephones, comprising a receptacle containing an antiseptic medium and provided with a central opening, a piece of fabric arranged across said opening and having its edge portions in contact with said antiseptic medium, and a cap or cover having a flange provided

with a groove or channel that receives attaching devices on said receptacle; substantially as described.

18. An antiseptic attachment for telephones, comprising a fabric arranged across the opening between the mouth-piece and the diaphragm of a telephone, in combination with a reservoir for antiseptic material which supplies said fabric; substantially as described.

19. An antiseptic attachment for telephones, comprising a fabric stretched across the opening between the mouth-piece and the diaphragm of a telephone, an encircling reservoir, and absorbent material saturated with an antiseptic solution and arranged in said reservoir in contact with said fabric; substantially as described.

20. In an antiseptic attachment for telephones, the combination with a casing having an inwardly extending boss, a fabric arranged across said boss, means for holding said fabric in position, and absorbent material saturated with an antiseptic material in contact with said fabric; substantially as described.

21. In an attachment for telephones, the combination with a casing having an inwardly extending boss, a fabric stretched across said boss, absorbent material saturated with an antiseptic medium in contact with the marginal edges of said fabric, and means for holding said fabric and said absorbent material in position; substantially as described.

22. In an antiseptic attachment for telephones, the combination with a casing having means at one side for attachment to the face plate of a telephone or diaphragm box, and means at the other side for attachment

of the mouth-piece of the telephone, said casing being provided with an opening located in alignment with the mouth-piece and the diaphragm of the telephone, a fabric extending transversely across said opening, and absorbent material saturated with an antiseptic material in contact with the marginal edges of said fabric; substantially as described.

23. The combination with the face plate of a telephone transmitter, of a casing removably secured thereto and containing an antiseptic medium, and a clip secured in said removable casing and engaging the face plate so as to lock said casing in position on said face plate; substantially as described.

24. In an antiseptic attachment for telephones, the combination with a fabric interposed between the mouth-piece and the diaphragm, means for supplying said fabric with an antiseptic medium, and a protecting screen arranged in juxtaposition to said fabric; substantially as described.

25. In an antiseptic attachment for telephones, the combination with a casing having an inwardly extending boss, a fabric arranged across said boss, absorbent material saturated with an antiseptic compound in contact with the marginal edges of said fabric, and a spring clip having radial enlargements for embracing said boss to hold said fabric and said absorbent material in position; substantially as described.

In testimony whereof I hereunto affix my signature in the presence of two witnesses, this fifteenth day of January 1908.

FRANK C. TABLER.
